UNITED STATES PATENT OFFICE.

CHARLES W. HUFSCHEIMDT, OF PRAIRIE DU CHIEN, WISCONSIN.

DESIGN FOR A BOOK-BACK.

SPECIFICATION forming part of Design No. 31,674, dated October 17, 1899.

Application filed October 13, 1898. Serial No. 693,454. Term of patent 7 years.

To all whom it may concern:

Be it known that I, CHARLES W. HUFSCHEIMDT, a citizen of the United States, residing at Prairie du Chien, in the county of Crawford and State of Wisconsin, have invented and produced a new and original Design for a Book-Back; and I do hereby declare the following to be a full, clear, and exact description of the same, reference being 10 had to the accompanying drawing, forming a part thereof.

This invention relates to backs, covers, or protectors for memorandum-books, leaves, and like articles generally incased to afford 15 protection.

The invention consists of the novel design of book-back which hereinafter will be more fully disclosed and particularly illustrated in the drawing hereto attached, which is a 20 perspective view thereof extended.

The book-back is of ordinary construction and comprises the sides 1 and the intermediate flexible part 2. One of the sides has a pocket 3 applied exteriorly thereto and disposed longitudinally and parallel with the 25 inner and outer edges of the said side. The sides 1 are flat, and the pocket 3 has its outer wall transversely bulged or outwardly curved, the longitudinal edges being straight and 30 parallel and vanishing into the plane of the

side. The lower or closed end 4 of the pocket is rounded or blunt and curves longitudinally and transversely and disappears at its edges into the plane of the side. The upper or open end of the pocket 3 has the top edge of 35 its outer wall depressed at a central point on a down curve, as shown at 5, and the portions at the sides of the depression 6 upwardly and outwardly curved, as at 6, and again inwardly curved, as at 7.

The essential feature of the invention is a 40 design for a book back or cover, one of the sides having a longitudinally-disposed pocket, with its edges vanishing into the plane of the said side and having its lower end round or blunt and its upper end centrally depressed and curved upwardly, outwardly, and inwardly at each side of the central depression.

Having thus described the invention, what 45 is claimed as new, and desired to be secured by Letters Patent, is—

The design for a book-back, substantially as herein shown and described.

In testimony whereof I affix my signature in presence of two witnesses.

CHARLES W. HUFSCHEIMDT.
